DISPENSER FOR FOLDED PAPER TOWELS

Vincent C. Jones and William S. Huss, Appleton, and Archie S. Krueger, Green Bay, Wis., assignors to American Can Company, New York, N.Y., a corporation of New Jersey

Filed Oct. 6, 1960, Ser. No. 62,392

Term of patent 14 years

(Cl. D52—2)

Fig. 1

Fig. 2

Fig. 3

Fig. 4

The undisclosed side of the dispenser is substantially the same in appearance as the side shown.

We claim:

The ornamental design for a dispenser for folded paper towels, as shown and described.
